(57) **CLAIM**

What is claimed is the ornamental design for a display screen with graphical user interface, as shown and described herein.

DESCRIPTION

FIG. 1 is a front view of a first embodiment of a display screen with graphical user interface, showing the new design; and,

FIG. 2 is a second embodiment thereof.

The broken lines showing a device illustrate environmental structure and form no part of the claimed design. All other broken lines show portions of the graphical user interface and form no part of the claimed design. The outer solid line rectangle showing the display screen forms part of the claimed design.
